UNITED STATES PATENT OFFICE.

JOHN M. LARSON, OF CHICAGO, ILLINOIS.

REGULATOR.

1,404,776.

Specification of Letters Patent. Patented Jan. 31, 1922.

Application filed February 11, 1916. Serial No. 77,633.

To all whom it may concern:

Be it known that I, JOHN M. LARSON, a citizen of the United States, residing at Chicago, in the county of Cook and State of Illinois, have invented new and useful Improvements in Regulators, of which the following is a full, clear, concise, and exact description, reference being had to the accompanying drawing, forming a part of this specification.

My invention relates to improvements in regulators and is especially applicable to regulators used in connection with dampers. It has for its object the production of a device that is adjustable for either pressure or vapor.

A further object is the production of a device that can be made universal for all heating boilers.

20 A further object is the production of a device in which the fulcrum may be shifted.

A further object is the production of a device of cheap and simple construction and one not liable to get out of order.

25 These and such other objects as may hereinafter appear are attained by my device, an embodiment of which is illustrated in the accompanying drawings, in which—

Fig. 1 represents a side elevation of my 30 device in operative position;

Fig. 2 represents an enlarged sectional view of my device;

Fig. 3 represents a top plan view of Fig. 2;

35 Fig. 4 represents a sectional view through the line 4—4 of Fig. 2 looking in the direction indicated by the arrows;

Fig. 5 represents a horizontal sectional view on the line 5—5 of Fig. 2 looking in the 40 direction indicated by the arrows.

Fig. 6 is a section on the line 6—6 of Fig. 2.

Like numerals of reference indicate like parts in the several figures of the drawing.

45 Referring now to the drawings, A represents a boiler on which is mounted my device B adapted to operate the furnace door C. Mounted on top of the boiler A is a steam pipe 6 in open communication with 50 a diaphragm case 7 within which is mounted a series of diaphragms 8 on the top of which is mounted a stem 9 sliding within the opening 10 in the top of the diaphragm case. No claims are made for novelty in the 55 diaphragm in this application. On the top of the stem 9 is mounted the lever support 11

carrying the lever 12 on which are preferably mounted weights 13, 14, and from one end 15 of the lever, a chain 16 connected with the furnace door C. This lever support comprises a U-shaped yoke 17, having oppositely disposed threaded openings 18 in its sides. Screws 19, 19 extend through these openings and are provided with nuts 20 holding the screws in place. The ends of the 60 screws are tapered, forming conical surfaces as indicated at 21. Loosely fitting within the yoke 17 is a rectangular collar 22 through which the lever 12 passes, a screw 23 extending through the top of the collar 70 and engaging the lever holding it rigidly in position. The rectangular collar is pivotally mounted on the conical ends of the screws 19 as shown most clearly in Fig. 4, the ends of the screws fitting within the concave sockets 24 in the sides of the rectangular collar. 75 It will be noted that I provide three pairs of oppositely disposed sockets so that the horizontal position of the lever may be varied if desired to accommodate existing circumstances.

As shown in Figs. 2 and 5, I provide a supporting plate or guide 25 having a plurality of oppositely disposed ears 26 through which screw bolts pass, securing the plate to the 85 top of the casing. This plate is channelled out at its under surface providing for the insertion of a square nut 27 and a longitudinal slot 28 in its upper face permit the insertion of a screw bolt 29 engaging the nut 90 27. This slot is directly under the lever 12 and extends in a line therewith.

Mounted on the stem 9 is a connector yoke 30 similar in all respects to the lever support 17. A rectangular collar 31 through 95 which the lever 12 passes is also mounted in this support, the collar and connector yoke being preferably precisely the same as the support shown in Fig. 4. The only difference between the two is that the connector 100 yoke is adapted to move up and down as the pressure within the diaphragm raises or lowers the upper face thereof, while the fulcrum support is held against vertical movement by the nut 27 within the channel or 105 way of the plate 25, but can be slid forward or back in the line of direction of the lever itself, forming in effect a shifting fulcrum for the lever 12. The connector yoke 30 is provided with screw-threaded openings 18^a 110 and screws 19^a, similar to the screw-threaded openings 18 and screws 19 previously de-

scribed. The screws 19^a are provided with conical points 21^a for cooperation with conical depressions 24^a in the collar 31. The collar 31 is provided with a screw 23^a for securing it to the lever 12 in any adjusted position.

My device is adapted for use on various devices, the universal adjustment feature making it applicable for pressure or vapor, 10 by changing the fulcrum position and shifting the weights and levers. It can also be used for the control of pressure reducing valves, pressure governors, etc., as well as for regulating the ordinary types of boilers. 15 Certain styles of boilers require an unusually large movement of the power lever in order to open and close the damper. In other cases the connecting chains become shortened or lengthened or bind on pulleys 20 rendering it extremely essential to have some adjustment features present, by means of which the pressure may be accurately controlled. The efficiency of the regulator is also often greatly impaired by accumulation 25 of rust and dirt where they are installed in places not easily accessible. By the use of my shifting fulcrum, however, I can secure as much or little power as desired and can render the device highly sensitive, such 30 sensitiveness being easily adjusted by moving the fulcrum support toward or away from the connector, and to do this it is simply necessary to loosen the nut 27 and the screw 23^a, when the fulcrum support may be slid 35 along to any position, for instance, that shown in dotted lines in Fig. 2. The nut 27 and the screw 23^a are then tightened, and the device is ready for use. When it is desired 40 to remove the fulcrum support, the nut 27 is loosened, also the screw 23^a and the fulcrum support 30 and the collar 31 can then be slipped off of the lever.

It is apparent that my device is capable of universal use on all heating boilers and is 45 very easily installed.

While I have shown a specific adjusting means through the medium of which the fulcrum support may be shifted on the diaphragm case, it is evident that the same results 50 may be attained by a convex plate on a diaphragm case adjustably connected to the lever; this, however, or other devices of a like nature accomplishing the same result comes well within the scope of my invention.

Having thus described my invention, what I claim as new and desire to secure by Letters Patent is:

1. A regulator comprising a diaphragm, a 60 diaphragm casing, a diaphragm stem passing through said casing, a collar, a lever mounted on said stem and actuated thereby and supported by said collar, a fulcrum for said

lever mounted on the casing, and means whereby said lever may be shifted vertically 65 with respect to said fulcrum to vary the point of pivotal connection between said fulcrum and lever.

2. In a device of the class described, the combination with a diaphragm, a diaphragm 70 casing, a stem extending through said casing, a fulcrum support mounted on said casing, a lever supported thereby, yoke members mounted on said stem and fulcrum support respectively, collars surrounding said lever 75 and secured within said yokes, and means for permitting the vertical shifting of said collars and lever.

3. In a device of the class described, the combination with a diaphragm, a diaphragm 80 casing, a stem extending through said casing, a fulcrum support mounted on said casing, a lever supported thereby, yoke members mounted on said stem and fulcrum support respectively, collars surrounding said lever 85 and means integral with said collars for supporting said lever in different positions of vertical adjustment.

4. The combination with a diaphragm and diaphragm casing, of a fulcrum member 90 mounted on said casing and laterally adjustable thereon, a lever pivotally connected with said fulcrum member and vertically adjustable thereon, and a pivotal connection between said lever and diaphragm provided 95 with means whereby the distance of the lever from the diaphragm may be varied.

5. The combination with a diaphragm and a diaphragm casing, of a yoke mounted on said casing and laterally adjustable thereon, 100 a collar pivotally mounted in said yoke and vertically adjustable therein, a lever slidably secured in said collar and means for connecting said lever to said diaphragm.

6. The combination with a diaphragm and 105 diaphragm casing, of a laterally adjustable fulcrum, a lever fulcrumed thereon, a yoke mounted on said casing having a stem passing therethrough and connected with the diaphragm, a collar pivotally mounted in said yoke and vertically adjustable therein and slidably connected with said lever.

7. The combination with a diaphragm and diaphragm casing, a connection yoke mounted on the casing and connected with the diaphragm, a fulcrum yoke mounted on the casing and adjustable relatively to the connection yoke, collars pivotally mounted in said yokes and vertically adjustable therein, and a lever slidably mounted in said collars. 115

In witness whereof, I have hereunto subscribed my name in the presence of a witness.

JOHN M. LARSON.
